UNITED STATES PATENT OFFICE.

MORTIMER G. MERRITT AND GEORGE S. HEATH, OF SPRINGFIELD,
MASSACHUSETTS.

MECHANISM FOR ROTATING THE PLATENS OF TYPE-WRITING MACHINES.

SPECIFICATION forming part of Letters Patent No. 442,129, dated December 9, 1890.

Application filed August 4, 1890. Serial No. 360,912. (No model.)

To all whom it may concern:

Be it known that we, MORTIMER G. MERRITT and GEORGE S. HEATH, citizens of the United States, residing at Springfield, in the county of Hampden and State of Massachusetts, have invented new and useful Improvements in Mechanism for Rotating the Platens of Type-Writing Machines, of which the following is a specification.

This invention relates to type-writing machines, the object being to provide improved means for rotating the platen of said machines; and the invention consists in the peculiar construction and arrangement of the platen-rotating devices, all as hereinafter fully described, and pointed out in the claims.

In the drawings forming part of this specification, Figure 1 is a perspective view of one end of the platen of a type-writing machine having applied thereto means for rotating the same embodying our improvements, this figure showing also one end of the platen-supporting frame. Fig. 2 is a transverse section of said platen about on line 2, Fig. 4. Fig. 3 is a transverse section of the platen about on line 3 of Fig. 4. Fig. 4 is a longitudinal section of the end of the platen to which the devices for rotating the same are attached.

The within-described improved platen-rotating devices are adapted to provide for the rotation of the platen within its supporting-frame in either direction by grasping the finger-wheel on the extremity of the shaft of the platen, the latter upon the release of said finger-wheel invariably becoming locked by the action of certain mechanism connected with the platen-shaft, said mechanism acting also through an attempt to rotate the platen by said finger-wheel to unlock the platen and permit its rotation thereby.

Other mechanism, as fully described below, is provided for rotating the platen in one direction by operating a horizontally-extending finger-lever for the purpose of spacing the lines of the writing.

In the drawings, 2 is the platen, of the usual hollow cylindrical construction, consisting of the inner metallic cylinder 3, having metallic heads 4, screwed or suitably attached to each

end thereof, (one only of which heads is shown in the drawings,) the heads 4 having an inwardly-extending hub 5 thereon to constitute proper bearings for the shaft 6 of the platen. The said cylinder 3 is in practice provided with a suitable surface, of rubber or similar material, to form a bed against which the paper lies to be struck by the type. The shaft 6 of the platen extends through the latter, and the ends thereof project beyond the heads 55 thereof and enter the end portions of the platen-frame 8, and the shaft is supported to rotate therein when the platen is turned.

Within the cylinder 3, near one end thereof, is secured in a suitable support 9 a vibratory latch 10, which is pivoted to said support by its rear end at α , Fig. 4, the free end of said latch extending through an opening β in the head 4, which allows said free end a certain degree of movement toward and from 60 the shaft 6. A spring 12 (shown in partly full and partly dotted lines in said last-named figure) serves to swing the free end of said latch toward the platen-shaft.

To provide means for swinging the free 65 end of the latch 10 from shaft 6, for a purpose below described, a cam-lever 13 is rigidly secured on shaft 6 by a screw or otherwise whose extremity has a recess therein to receive the edge of said latch, having cam-shaped or curved edges extending each way from its deepest point to the opposite edges of said cam-lever, as clearly shown in Fig. 2. It will be clearly seen that by turning shaft 70 75 80 85 90 95 100 6 in either direction one of said curved edges of the lever 13 is driven against the edge of the latch 10, causing it to swing in a direction from shaft 6, and upon swinging the lever back to the position shown in Fig. 2 spring 12 carries the latch again into the recess in the end of said lever.

A finger-wheel 14 is rigidly secured on the outer end of the shaft 6, which provides one means for turning said shaft and the platen, as below described.

A ratchet-case 15, of suitable metallic construction and of cup form, is supported indirectly on shaft 6, between the head 4 of the cylinder 3 and said finger-wheel. A sleeve 16 on shaft 6 extends from the inner end of 100

- the hub of said finger-wheel to the outer side of the cylinder-head 4, as shown in Fig. 4, and said ratchet-case 15 has its central bearing directly on said sleeve, the edge of said cup having a position close to the outer side of said head 4 and being retained in that position by the frame 8 outside of the cup, a pin or screw *y* securing the cup to the frame. Within the ratchet-cup 15 are located a toothed wheel 17 and a ratchet-wheel 18, which are secured together as one wheel (with an intermediate separating-disk 19) by one or more rivets 20, (see Fig. 3,) and said wheels 17 and 18 rotate freely on said sleeve 16, and
- 15 the free end of said latch 10 has an engagement with said toothed wheel, as shown.
- A pawl-arm 21 is hung on the sleeve 16 between the ratchet-wheel 17 and the adjoining inner side of the case 15, and has a swinging movement thereon. A spring 22, (see Fig. 3,) secured to case 15, has one end bearing on said pawl-arm to swing it downward and another end thereof bearing on a retaining-pawl 23, hung on the inside of case 15 and engaging with the ratchet-wheel 17.
- 20 The pawl-arm 21 has a pawl 23' hung thereon which engages with said ratchet-wheel to turn it, and is held in such engagement by a spring *o*.
- 25 A pawl-stop 24, having an operating-handle *c* thereon projecting through the rim of the ratchet-case, is pivotally hung on the inner side of the latter, and the different positions to which said stop may be swung govern the extent of the swinging movement of the pawl-arm 21, and consequently the degree of rotation of the ratchet-wheel and the platen, either to cause the spaces between the lines of writing on paper held on the platen
- 30 to be wide or narrow. Thus, with the stop 24 in the position shown by full lines in Fig. 3, the arm 21 and its pawl 23' may swing to the greatest extent, as indicated by dotted lines in said last-named figure for a wide-line space;
- 35 but if said stop be turned to the position indicated by dotted lines in said Fig. 3 the end of the pawl will, when moving the ratchet-wheel, engage with the end of the stop and permit a movement only for a narrow-line space. Said pawl-arm is operated by a horizontally-extending line-spacing lever 25, (extending toward the operator,) which is pivotally hung on the frame 8 of the platen, and has its inner end *K* turned at right angles to
- 40 its main part and extending through a slot *h* in the end of the ratchet-case to a position under said pawl-arm 21, whereby the latter and the pawl 23' are lifted when the outer end of lever 25 is swung downward.
- 45 The operation of the within-described improvements in turning the platen 2 for regularly spacing the type-writing lines on paper held thereby and for rotating the platen independently of said line-spacing lever to facilitate the placing of the paper in writing position thereon is as follows, it being understood that with the latch 10 in the position

shown in the drawings the platen is locked against rotation, except by lever 25 or wheel 14. The end of a sheet of paper is entered 70 between a paper-holder *D* and the platen 2. Then to quickly draw the end of the sheet around the under side of the platen and beneath the paper-guide *b* to a position to be printed on the operator grasps the finger-wheel 14, and, turning the same and through it shaft 6, swings the cam-lever 13 against the latch 10, (but not away from it,) and forces the latter downward out of engagement with the toothed wheel 17, (which is, as aforesaid, 80 attached to the ratchet-wheel 18.) This disengagement of latch 10 permits the quick rotation of the platen by the wheel 14 independently of the ratchet devices in case 15. Upon the release of the wheel 14 by the operator, the lever 13 and latch 10 resume their 85 normal positions, as shown in Figs. 2 and 4, by the action of the spring 12, which forces the end of latch 10 against one of the curved edges of lever 13.

90 While an operator is using a type-writing machine having thereon this description of a platen and rotating devices therefor, the line-spacing rotary movements of the platen are effected by pressing downward the free end 95 of the finger-lever 25, and, as above described, the pawl-arm 21 is thereby swung upward, and its pawl is engaged with the ratchet-wheel 18, turning the latter and the toothed wheel 17, and, owing to the engagement of the 100 latter with the latch 10, the platen 2 is caused to rotate coincidentally with said wheels 18 and 17.

105 The horizontal arrangement of the lever 25 for turning the platen for line-spacing, as described, is particularly advantageous as compared with the ordinary down-hanging lever generally used for this purpose, for downward pressure on the end of said lever to turn the platen in no way disturbs the position of 110 the platen-frame; but in operating the platen by said down-hanging lever the frame is often-times lifted and becomes moved out of place.

What we claim as our invention is—

1. In combination with the platen of a type-writing machine and the shaft thereof, a latch pivoted within the platen, having a vibratory motion toward and from the axis thereof, a spring to swing one end of said latch toward said axis, a cam-lever on said shaft acting to depress said latch, a toothed wheel mounted on said shaft in proximity to the free end of said latch, with which the latter engages, and a finger-wheel fixed on said shaft by which to rotate it and the platen coincidently, substantially as set forth.

115 2. In combination with the platen of a type-writing machine and the shaft thereof, a ratchet-case mounted thereon at one end of the platen and fixed to the frame thereof, a sleeve passing through said frame and case, within which said shaft rotates, a ratchet-wheel and a toothed wheel mounted and having coinciding rotary motion on said sleeve

within said case, a latch pivoted within the platen, normally engaging with said toothed wheel, a cam-lever on said shaft engaging with said pivoted lever, and a spring holding said latch in engagement with said cam-lever and wheel, a pawl-arm within said case, carrying a pawl in engagement with said ratchet-wheel, and an operating-lever hung on the platen-frame, having one end engaging with said pawl-arm, substantially as set forth.

3. In combination, a platen for a type-writing machine and a shaft on which the same is supported, a pawl-and-ratchet mechanism comprising an operating-lever therefor applied in relation to said shaft, and a latch to

act as a clutch between the said ratchet mechanism and said shaft and platen, and a cam on said shaft adapted on the turning of the shaft in either direction to move the latch to disengage the clutch connection between the platen and shaft and the ratchet mechanism, whereby the continued rotation of said shaft may be had independently of the ratchet mechanism, for the purpose set forth. 20
